UNITED STATES PATENT OFFICE.

CHARLES WALES, OF DETROIT, MICHIGAN, ASSIGNOR TO ADDER MACHINE COMPANY, OF DETROIT, MICHIGAN, A CORPORATION OF NEW JERSEY.

PNEUMATIC MOTOR FOR ADDING-MACHINES.

No. 880,607.

Specification of Letters Patent.

Patented March 3, 1908.

Application filed August 28, 1905. Serial No. 276,117.

To all whom it may concern:

Be it known that I, CHARLES WALES, residing at Detroit, in the county of Wayne and State of Michigan, a citizen of the 5 United States, have invented certain new and useful Improvements in Pneumatic Motors for Adding-Machines, of which the following is a specification, reference being had therein to the accompanying drawings.

10 The invention relates to an improved actuating device for adding machines, and consists in the construction of such an actuating device comprising a pneumatic motor for operating the rock shaft, a valve 15 controlling said motor, means for opening said valve, and means controlled by the operated device for holding said valve open a sufficient time to complete the stroke, and then to close the same.

20 The invention further consists in the construction, arrangement and combination of the various parts as more fully hereinafter described and particularly pointed out in the claims.

25 In the drawings, Figure 1 is a vertical central cross section through the casing in which is arranged the pneumatic motor, the controlling valves and the pump; the section being through the same; Fig. 2 is a section 30 on line $x-x$ of Fig. 1; Fig. 3 is a perspective view of one end of the actuating lever for the crank shaft, showing the means for holding the valve open, so that the motor will complete its stroke, and for permitting it to be 35 closed at the end of the stroke; Fig. 4 is a side elevation of the same parts, showing them in a different position.

A represents in diagram any suitable adding machine, of which B is the crank shaft 40 and C the crank arm or lever by which the adding mechanism is actuated. In the ordinary use of this device, the operator sets the adding devices and then rocks the lever C back and forth for the purpose of operating 45 such device. My invention is the application of a pneumatic motor for rocking this rock shaft, so that all the operator has to do is to trip a valve and the motor operates the crank shaft a single time and then stops.

50 To the rock shaft is attached a rock arm C' which is connected by the link D to the lever E and this lever is connected by the link a to the upper board b of a bellows F which in this case forms the pneumatic 55 motor for operating the crank shaft. This

motor is supplied with air from any suitable source and has supply and exhaust valves. I have shown in this application an electrical motor G driving a crank shaft G' which crank shaft operates the pumping bellows H 60 of which I have shown three, operated from a single shaft and leading through the passage I to a common discharge pipe I'. At some point, the discharge pipe conduit from the air pumps is provided with a storage 65 bellows J which I have shown as normally held in or towards its contracted position by the springs J' thus giving a uniform tension or pressure to the air. I have also shown an inwardly-opening check-valve c in this bellows with its stem projecting outwardly, so that when the pressure becomes sufficient to inflate the bellows to near its limit, it will strike a stop such as the side of the outer casing K of the machine and slightly open 70 the valve so as to relieve the pressure, said check valve, together with the bellows, forming a motor regulator.

The air passes from the conduit I into the pressure chamber L. In this pressure 80 chamber is a port d leading to a passage e which in turn leads to the interior of the bellows or motor F, as shown in Fig. 1. Opposite the port d is the exhaust port h and the valve c is adapted to be moved so as to 85 open or close either the port d or the port h. The valve is connected to a stem i which is connected to the movable board of a small bellows pneumatic or what I term a secondary motor k. This pneumatic k is in the 90 chamber L and the pressure in that chamber will tend to hold this pneumatic collapsed. Leading from this pneumatic is a passage m having an inlet port m' from the air chamber L and this port is controlled by 95 a valve n which also controls the exhaust port o.

p is the stem of the valve o which is connected to a bell crank lever M. Connected to this bell crank or to the valve stem is a 100 spring N tending to hold the valve down, so as to close the port m' and open the exhaust port o in the normal position of the parts. Connected to the bell crank M is a connecting rod O which at its outer end is connected 105 to a bell-crank P and this in turn is connected to the connecting rod Q having the finger board or presser Q' at the upper end, and arranged conveniently beside the key board (not shown) of the adding machine. On the 110

lever E is a segmental flange R and on the end of the connecting rod O is a laterally-projecting roller wrist S in the place of the segmental flange R.

5 The parts being thus constructed their operation is as follows:—The motor G will operate the pumps H and pump the air into the reservoir J, where it will be maintained at substantially uniform pressure therein 10 and in the chamber L. The pressure of the air in the chamber L will normally maintain the pneumatic k collapsed and will thus hold the valve c' in its upper position in which position the exhaust port h is connected with 15 the interior of the bellows F and the air supply is cut off therefrom. To operate the rock shaft B, the operator presses down on the presser bar Q', which through the bell-crank P, connecting rod O, bell-crank M and stem p, will move the valve n so as to open the port m' and close the exhaust port o. This will admit air into the interior of the pneumatic k which will be immediately expanded and will shift the valve c' so as 20 to establish communications between the chamber L and the passage e and at the same time close the exhaust port h. This will admit air under pressure into the bellows F which will immediately be inflated, 25 thereby rocking the lever E and drawing on the crank arm C' and rocking the crank shaft B. It is necessary to hold the valves in this position during the upward movement of the bellows board b so as to complete the stroke 30 thereof and this I accomplish by the following mechanism: When the operator presses on the presser bar Q', the connecting rod O is moved horizontally so that the roller wrist S is moyed behind the path of 35 the flange R. As soon as the motor starts to rock the lever E, the flange R is moved in front of the roller wrist and thus the valves are maintained in this position until 40 the lever has traveled the entire length of the flange R. As soon as the flange passes below the roller wrist S, the spring N will be free to act and will rock the bell cranks and the connecting rod O so that the roller wrist S is projected in front of the flange R, thus 45 reversing the position of the valves n and c' from that described to that shown in Fig. 1. The valve n is closed by the spring N and the exhaust port o simultaneously opened so that the air in the chamber L will collapse 50 the pneumatic k and thus will shift the valve c' to close the air inlet port to the motor and open the exhaust port h. At the same time the weight of the movable board of the bellows motor (or a spring if desired) will rock 55 the shaft back to its initial position.

The device thus constructed is simple and cheap to manufacture, is exceedingly rapid in its operations, and with such a device all the operator has to do is to set the adding 60 mechanism by the ordinary keys and then

touch the presser bar Q', when the motor will rock the shaft B the same as it would if operated by hand, and when it has been given a single actuation, the motor stops. The presser bar Q' with its connected mechanism is simply a tripping device or a tripper for shifting the controlling valve and the valves are then controlled by the actuated mechanism. While I have shown a specific form of this controlling and actuating device, it is 70 obvious that many changes may be made in the details, without necessarily departing from the spirit of my invention. 75

What I claim as my invention is:—

1. The combination with the actuating shaft of an adding machine, of a reciprocating pneumatic motor for rocking said shaft, valve-controlled inlet and exhaust ports for said motor, a tripper for opening the inlet port, and automatic means for holding said port open a sufficient time for completing the actuating movement of said shaft, and then to close it and open the exhaust port. 80

2. The combination with the actuating shaft of an adding machine, of a reciprocating pneumatic motor for rocking said shaft, valve-controlled inlet and exhaust ports for said motor, a tripper for starting the motor, and automatic means for controlling the inlet and exhaust ports of the motor to cause it to 90 rock the shaft forward and back, and to stop, after each tripping operation. 95

3. The combination with the actuating shaft of an adding machine, of a reciprocating pneumatic motor for rocking said shaft, a valve for controlling the inlet and exhaust to said motor, a tripper for opening the inlet and closing the exhaust, means controlled by the movement of the rock shaft for holding the valve in this position during the actuating movement of the shaft, and for releasing and shifting the valve at the end of such movement. 100

4. The combination with the actuating shaft of an adding machine, of means for 110 rocking said shaft comprising a bellows connected to rock said shaft by its inflation and deflation, a valve controlling the air to and from said bellows, and a tripper for operating said valve. 115

5. The combination with the actuating shaft of an adding machine, of means for 120 rocking said shaft comprising a bellows connected to rock said shaft by its inflation and deflation, a valve for controlling the passage of air to and from said bellows, a tripper for opening said valve, and means after the valve is opened for holding it open until the shaft has completed its actuating movement, and then closing it. 125

6. The combination with the actuating shaft of an adding machine, of a crank arm thereon, a reciprocating pneumatic motor connected to said crank arm, a valve for controlling the inlet and exhaust thereto, a pneu- 130

matic for operating said valve, a secondary valve for the pneumatic means for normally holding the secondary valve closed, and a tripper for opening it.

5. 7. The combination with the crank shaft of an adding machine, of an air pump, a regulator for maintaining a uniform pressure, a reciprocating air motor, a connection from the motor for rocking the crank shaft, a valve 10 controlling the motor, means for opening the valve, and means controlled by the motor for holding said valve open and closing the same automatically.

8. The combination with the actuating 15. shaft of an adding machine, of a reciprocating pneumatic motor connected to rock said shaft, a valve for controlling said motor, a secondary pneumatic motor for controlling said valve, a valve controlling said secondary

motor, means for opening said valve, and 20 means controlled by the operated devices for holding it open during the completion of one operation and closing it.

9. The combination of a pump, a pressure regulator on the exit conduit, an air chamber, 25 a motor, a valve-controlled conduit from the chamber to the motor, a valve for the motor, a secondary motor for controlling the valve, a valve controlling said secondary motor, means for opening said valve and means for 30 holding the valve open during a single actuation of the motor and then closing the same.

In testimony whereof I affix my signature in presence of two witnesses.

CHARLES WALES.
